UNITED STATES PATENT OFFICE

2,031,764

PHOTOELECTRIC MUSICAL SYSTEM

Ivan Eremeeff, Philadelphia, Pa.

Application March 15, 1934, Serial No. 715,656

27 Claims. (Cl. 84—1)

My present invention relates to a complete electronic musical system which embraces a novel art of preparation of records, wave synthesis, and sound reproduction. An object of my invention is to devise an electronic musical instrument whose major musical effects resemble the keying touches of a piano and an organ, such instrument being separate or in combination with a sound reproducer.

Another object of my invention is to provide as an important part of this system, the novel processes of preparation, recording, and reproducing of photographic sound wave patterns.

It is a further object of my invention to provide an electronic musical instrument which employs a pitch film and a quality film. The pitch film is made as a running belt which is endless as the result of accurate and precise splicing. Provision is also made for the adaptation, if desired, of a slotted revolving drum, in lieu of the film, or a multi-planed revolving scanning mirror. This musical system is provided with precaution against rubbing or wearing of the films used for pitch and for quality, by means of rollers which are so designed that the film runs over padded surfaces. The quality film is stationary excepting during intervals when it is adjusted to desired positions, either manually or by motorized drive. The quality waves are focused on running scanning pitch slits, instead of the pitch slits being focused on the quality waves as in motion picture scanning.

This electrical musical instrument provides a motorized unit for each keyboard, novel speed controlled tremolo and volume control means which do not interfere with the tone quality, and a diminishing apparatus for sustaining tones, which also permits of the production of staccato effects. The instrument utilizes a variable intensity light source for distribution of the light intensities according to waves of different frequencies. No electrical circuits are used in the actual sound work, excepting in parts such as the amplification, the photoelectric cell connection, lighting, etc.

The instrument is provided with novel and efficient light shutters which overcome area loss, such shutters having packing which is provided for the purpose of closing out undesirable escaping light, said shutters also having novel flexible keying connections. The keys are made of hollow stamping metal or die casting, instead of the conventional wood as in organs and pianos. Since most of the instrument is constructed of metal, I find it advantageous to have metal keys, also,

due to higher efficiency and greater accuracy. The instrument employs synchronous brushless induction motors near its sensitive circuits, and a novel quality film winding device is provided with graduated degree markings for the indication of each quality section.

Another object of my present invention is to provide a meter for indicating the sound intensity, which is also applicable for recording any other measured values for which a galvanometer is used.

A further object of the invention is to devise a sound reproducing device, in which a quality film is continually running from one roller to another. Said film carries a plurality of individual tracks of recording, which are made simultaneously, each track representing a complete quality, which is selected by its own co-operative key in a keyboard, at a predetermined pitch. Light is focussed on all tracks by means of a single lens. The reproducer employs its own volume control, tremolo control, and diminishing apparatus for creating different expressional effects. For the sake of compactness of construction, conventional typewriter keys may be utilized. A single filament lamp is used as a light source, which has moderate intensity, and is guarded by a plurality of light shutters. Said light source passes light into a specially corrected objective projection lens which is adapted for multi-tracks, picking up the image from a flat field and focusing it on a flat field without distortion at the edges or in the center.

It is a still further object of my invention to provide a novel process for the preparation of records, by which lines representing pitch slits or quality waves are drawn on mathematically ruled graph papers, which are photographed by novel photographing methods onto films or drums. In the preparation of pitch and quality wave patterns, this system embraces full wave modulation, additional synthesis of harmonics by one and two side modulation, spreading modulation, and methods of simplification of fixed wave forms at different frequencies, to ensure clear and efficient recording. The novel two-side recording is provided for the purpose of enlarging narrow angles for more accurate photography. This system also includes novel methods of preparing a single wave form pattern which produces several tones simultaneously from one key.

It is another object to show a number of diaphragmatic assemblies of my invention, with commercial design, also illustrating the final assembly into a cabinet.

Other objects and advantages in detail of con-

struction and operation will be apparent as the description proceeds, reference being had to the accompanying drawings, in which:—

Fig. 1 is a view of an electronic musical system.
5 Fig. 2 represents a sound on film apparatus which is an additional part of what is shown in Fig. 1.

Fig. 3 depicts a modification of the system shown in Fig. 1.
10 Figs. 4 and 5 represent quality and pitch films, respectively, as used in my musical system.
Fig. 6 is a view of diminishing and keying means.

Fig. 7 and Fig. 7' are detail views of a part of 15 what is shown in Fig. 6.

Figs. 8 and 9 illustrate methods for preparing records such as shown in Figs. 5 and 4.

Figs. 10 to 18, inclusive, represent diagrams illustrating modulating methods.

20 Fig. 19 represents the preparation of a sound pattern by the synthesis of harmonics.

Figs. 20, 21, and 22 depict sound waves representing different tone qualities, with their simplification for recording at different predetermined frequencies of a musical scale.

Fig. 23 represents a commercial unit assembly of what is shown in Fig. 1.

Fig. 24 represents a general complete assembly view of my musical system.

30 Figs. 25, 26, and 27 represent diagrammatically the wiring and sound distribution of my invention.

Referring to Fig. 1, 1 represents a pitch film which rides on several rollers such as 2, and 35 3, by aid of the motor 4, which has governor 4" and speed control 4''. The rollers are padded to avoid rubbing and wearing, and are connected by gearing so that the film does not require stretching. The gearing is illustrated in Fig. 23 and is not shown in Fig. 1 for the sake of simplicity.

The aperture shield 5 permits of focusing predetermined selective stationary wave images from the quality film 6 onto the running pitch film 1 by the objective projection lens 7, which is a specially corrected lens adapted for multi-tracks. Said lens picks up images from a flat field without distortion, so that the edges or sides of the images are equally as sharp as the center.

0 The variable translucency disc 8 interrupts light passing from lens 7 at predetermined speeds which are controlled by the pedal 9 for the production of tremolo effects without interfering with the tone quality of the output. The variable 5 transluency disc 10 is controlled by pedal 10' for regulating volume without interfering with the tone quality. By depression of the keys in the keyboard 11, predetermined amounts of light are permitted to pass through the pitch film 1 onto the photo-sensitive element 12 for conversion into electrical energy which is later amplified and issued as sound energy.

The screw 11' shown below the keyboard represents the adjusting means provided for each key, to determine the amount of its drop, thus controlling the amount of light passing through the space left as a result of lifting its co-operative light shutter. The quality film 6 is advanced and retarded to predetermined positions at desired intervals by the manual winding of crank 13 which is geared with the shaft of roller 14 in its pulled position, and engaged with shaft 15 in its pushed position, while, with the aid of a chain, it is engaged with roller 16. The shaft of roller 16 is provided with an indicator 16' which has

graduated degrees for pointing out the quality section selected. Light sources 18 consist of a plurality of lamps which are distributed in such a manner that those frequencies which require greater intensity are provided with lamps of lighter voltage. 19 is a motorized diminishing and keying means which is controlled in speed by a slipping clutch which forms a part of the pedal action 20 for speed variation, for longer and shorter time of tone diminishing for producing sustained and "fading out" tones after the keys of keyboard 11 have been released by the fingers. This diminishing and keying means is shown in detail in Figs. 6 and 7.

When a predetermined key is depressed, its 15 co-operative light shutter is raised to permit light from 18 to fall on a predeterminedly set wave track on film 6. Said track is illuminated, and its image is focused by lens 7 on the co-operative pitch track of the running pitch film 1, 20 which scans the focused and reduced image.

The motors used in this system near the sensitive circuits are brushless, being of an induction type, to avoid any parasitic noises. The large size of the quality film 6 permits the passage of 25 greater amounts of light, which is not intense enough to warp or fire the film. By the use of the large quality film, large light shutters are also employed, and the quality tracks also have comparatively large dimensions. The methods 30 of film splicing which I use in this system will be described later in the specification, with regard to Fig. 5.

Fig. 2 represents an additional sound on film apparatus which is controlled by the keys of the 35 keyboard 21, which are illustrated as conventional typewriter keys, for the sake of compactness of construction. The dot and dash lines on the keyboard 21 refer to a continuance of the keys shown, which are too numerous to illustrate. However, the regular keyboard such as 40 41 in Fig. 1 may be used in lieu of the typewriter keys. Each key has connection to its co-operative light shutter by means of the diminishing device 19. Light from the source 18', 45 which is a single filament type lamp, is focused by the corrected objective lens 7 through the shield 5' onto the running quality film 22. Said film is driven by the step pulley 23 from the motorized gear drive 24 at predetermined speeds. 50 The different steps of the pulley 23 correspond to the frequencies of a musical scale, as indicated by the chart 25, so that the film 22 may run at any predetermined speed. By raising any of the shutters by the keyboard 21, the image of the 55 filament is focused in the form of a light slit onto predetermined periodic and non-periodic wave tracks of the quality film 22.

Said film allows light to pass through its wave tracks in a shutter action manner to the photo 60 sensitive element 12 for conversion into electrical and sound energy. The pedals 10' and 9 are provided for controlling said light in order to produce such effects as tremolo and volume control, as described with reference to Fig. 1. The 65 sound on film system shown in Fig. 2 is an addition to the musical system described above with regard to Fig. 1. With the sound on film system, a musician or other operator, utilizes the already recorded music or speech at predetermined 70 pitches, controlled by himself. A musician, for example, mixes such music with his own musical rendition produced on the musical system as shown in Fig. 1 by playing one keyboard as 11! 75

in Fig. 1, with one hand, and playing with another hand on keyboard 21, as in Fig. 2.

Fig. 3 is a modification of what is shown in Fig. 1, without the moving film 1, which is shown in Fig. 1. Instead, the scanning is made by means of the multi-planed rotary mirror 15 and its drive 4', which reflects the image of the filament of the light source 18' when any of the shutters are raised by their co-operative keys. The objective lens 7 projects said light image onto predetermined wave tracks of the stationary quality film 6 by one-directional scanning. The image of the filament of lamp 18' is made to move in a scanning manner over the stationary quality waves in such a way that when said light image commences to scan the beginning of a wave, the scanning of the end of the preceding wave has already ceased. This system is provided with intense concentrated light which scans one or more wave lengths at one time, while in Fig. 1, a plurality of moderate intensity light slits compoundedly and simultaneously scan a plurality of quality waves, as explained in my co-pending patent applications, Serial Number 686,361, filed 25 August 23, 1933, and Serial Number 687,458, filed November 10, 1933.

The modified film shifting device 13' shows a pair of clutches as 26 and 27, which engage one at one time for forward and reverse movement 30 of the film 6 on suitable rollers. Each roller has provision for friction such as 28.

In order to indicate and measure accurately and represent numerically by a counter the volume of the light energy used in sound production from each key, or for any other measurements which I may wish to make in the future, I provide my system with a novel meter for this purpose. The output of the photosensitive element 12 actuates the galvanometer 32 proportionally, so that the greater the output of said photosensitive element, the greater is the deflection of the galvanometer mirror 29 on disc 30. Constant light energy as from the light source 18' is focused and reflected onto the galvanometer mirror 29 by means of the objective lens 29' to the transparent or opaque perforated rotary surface 30, which is coupled to the revolving mirror drive 4' with the aid of a chain 30'. In the case of employing an opaque rotary surface, it contains a plurality of rows of perforations as 30'' representing different frequencies, while if a transparent rotary surface is used, it contains a plurality of rows of opaque wave tracks as 30''' which represent different frequencies. Thus, signals are produced for driving a suitable registering device, such as a counter 34, when the light beam from source 18' passes with the aid of shutter 31, through the tracks of the surface 30 on the photo sensitive element 12' when galvanometer 32 is deflected by current from the circuit from the amplifier 32'' which is fed by line 12'' from the photo sensitive element 12 as a result of the impression of light energies passing from the actuation of predetermined keys of the keyboard 11. This meter is frequency operated, by which the galvanometer movements of measured quantities are multiplied by a light beam. Said light beam is interrupted by a so-called light chopper at different frequencies, provided for each angular deflection of the light beam in order to impress pulsating light energy on the photo sensitive element. With the aid of the amplifier 33, said photo sensitive element drives the device 34 for the purpose of indication and counting. Due to the universal applica-

tion of this meter, I do not wish to limit myself to using it only for measuring sound intensities.

Fig. 4 shows a section of a stationary quality film, with portions of different wave tracks such as 35, 36, etc. It can be seen that the width of the tracks is the same in low frequencies as in high frequencies, with modulations made from zero to 100% in order to obtain efficient cam action. The quality tracks as in the film 6 of Fig. 4, are enlarged proportionally in wave lengths to 10 correspond to the pitch film as shown in Fig. 5. For example, if the lowest frequency is 32 cycles per second and the pitch slits are $\frac{1}{2}$ inch apart at the track 31, then the quality track is enlarged, for example, by four times, making a wave length 15 of two inches in the wave track 38 of the quality film. Of course, the width of the quality wave track is also expanded accordingly. For example, if the width of the pitch track at 31 is .100", then the width of the quality track 38 is .400". 20 The width of the individual pitch slits of the pitch film are any suitable dimension. However, the finer the slit is, the finer is the scanning of the inequality wave, provided, of course, that the intensity of the light passing through it permits. 25

The pitch film shown in Fig. 5 is spliced at the portion a, b, c, d in the following manner:— the photographic emulsion from one end of the film is taken off without scratching, exactly on the line of, for example, c, d, which is placed 30 under the other end of the film at line a, b. Transparent film cement is used and the accurate matching of the tracks is made under magnification. The film then does not have any cause for producing an additional distorting 35 sound as it moves. Since the distance of the splice is only about $\frac{1}{8}$ inch, and also as the film runs for example, eighty feet per minute, the duration of the splice is not enough to cause any noticeable undesired noise. 40

Fig. 6 represents a keying and diminishing device which can be found in Figs. 1, 2, and 3. When the key 39 of the general keyboard 11 as shown in Fig. 1 is depressed in the direction indicated by arrow, the shutter 40 is lifted for example, one inch, opening a slit between the remaining shutters, through which the light from the source 18 falls on the quality film 6, shown in Fig. 1, passing into the previously described lens which focuses light on the running pitch film 50 which also has been explained. As the finger leaves key 39, the shutter 40 drops by its own weight and closes the small section of the quality track which it guards. This, of course, gives an organ action, in which the sound production ceases as the finger leaves the key, provided that the diminisher spring such as 41 is loosened by crank 42. Said crank moves frame 43 with the aid of the eccentric cams as 44 and 45. If crank 42 is set to its position for diminishing by stretching the springs as 41, the lifted shutter 40 will not fall to a resting position when the finger lifts from the key 39, but will be brought down at a predetermined rate of speed of the motor which is geared to rollers 46 and 47. When all the shutters are brought down to the stop 48, the rollers 46 and 47 are continuously rolling and the shutters are sliding easily. The rollers 46 and 47 roll continuously so that at any time the diminishing device can be put into operation. Staccato effects 55 are produced by the key being hammered by the hand, the key responding as quickly as the movements of the hand. 60

In Fig. 7, a depicts the shutters as 40, with their spacers 49, which are parts of the roller 46. The 75

flexible padding 50 closes out the light escaping through the gaps between the shutters. The padded shutter is shown in the detail b of Fig. 7.

Fig. 8 illustrates a method for the preparation of a pitch film. Mathematically calculated distances for each cycle and each frequency are prepared and rows of very fine lines are drawn or printed on non-shrinking flexible transparent or opaque material. The distances between the tracks are made, for example, one inch for the low frequency of C_1 . In C_2 the distance will be $\frac{1}{2}$ inch. In C_4 the distance will be $\frac{1}{4}$ inch, and so forth. The distance of $C\#_1$ will be only a trifle less than that of C_1 , which is inversely proportional to the difference between the notes C and $C\#$ of a musical scale. That is to say, as the frequency goes higher, the space becomes smaller. The surface of said material is, as I have mentioned, ruled with lines. These are predeterminedly drawn over in order to produce a record with slits of predetermined or desired size.

In Fig. 8 the opaque surface is shown placed over a suitable rotary drum, with edges cemented, and 51 represents a plurality of slits which have been drawn on said surface. When the drum is revolved, the slits are photographed by 52 onto the film 53 which rolls over the drum 54 in such a manner that when drum 54 revolves once, the slit drum also makes one revolution, due to the gear drive 55. Any length of the film as 53 can be utilized. Said film is positive when developed, as shown by 1 in Fig. 1. For substituting film 1.

Fig. 9 shows the material placed on a drum as in Fig. 8, with mathematically calculated distances. But, in lieu of slits, quality waves are drawn, such as 56, and the drum is brought closer to the lens to be photographed in large size on the film 57 which is then printed. Such a film is represented by 6 in Figs. 1, 3, and 4.

Figs. 10 to 18, inclusive, show wave patterns which are drawn on opaque surfaces with mathematically calculated dimensions for each frequency. As I have mentioned, the low frequency C_1 has, for example, one inch space, and Fig. 10 shows a wave pattern drawn in that space in repetition. However, for high frequencies, as in the seventh octave, for example, which affords only a space of $1/64$ inch, it is impossible to draw any pattern but a straight line, as shown in Fig. 11. As the frequencies go higher, the original wave form must be modified in order to provide sharper registration by the scanning slit which is sometimes only $1/64$ inch in width.

In Fig. 10 there is shown a pattern which is used for approximately the first to the fourth octaves, and only several steps are available for producing variation of light by the scanning slit. In Fig. 11 the wave represents only the highest octave, in which the black and white lines are nearly equal to the width of the scanning slit in the pitch film. In order to produce any quality in the high frequencies, I modulate the tops of the lines by a predetermined additional harmonic whose amplitude is, at the highest, about 10% of the entire width of the track.

Fig. 11 represents a track of for example, a 4000 cycle tone with modulation as 58, which is in the form of a harmonic of 500 cycles, which is combined with the 4000 cycle wave for the purpose of obtaining quality, which is in accordance with the synthesis disclosed in my patent of August 29, 1933, Number 1,924,713.

The wave shown in Fig. 12 resembles that of Fig. 11, but the synthesis of, for example, a 4000 cycle tone with a 500 cycle tone 58', is accom-

plished by narrowing and spreading the white lines, increasing 5% and decreasing 5%, totaling 10% modulation.

In Fig. 10 the low frequency permits of placing steps in each wave length. Additional direct synthesis is also made by cutting down the tops of the pattern for adding extra harmonics.

Fig. 13 shows a pattern which is modulated in Fig. 14 by spreading, such as shown in Fig. 12. The same pattern is shown in Fig. 15, modulated as in Fig. 14, by spreading, and in addition, the tops are cut down for producing an additional harmonic. In Fig. 16, the pattern shown in Fig. 13, having, for example, 1000 cycles, is synthesized by spreading, as shown in Fig. 14, to create an additional 200 cycle harmonic, synthesized with a 500 cycle harmonic, produced by cutting down the tops, and also synthesized with a harmonic of 800 cycles which is produced by cutting the bottoms. All harmonics are synthesized at predetermined intensities which are fractions of the full amplitude represented by the width of the wave patterns, as shown in Fig. 13.

Thus, the wave forms which modulate the light energy by cam action can also be modulated additionally, in three ways; first, by distortion of the wave patterns, second, by stretching, and third, by cutting the tops and bottoms in any predetermined periodic cycles. This is provided in order to produce additional synthesis of harmonics with fixed wave forms, which sometimes can be accomplished by additional alteration of already drawn waves. This system is capable of producing numerous combinations and alterations, and I do not wish to be limited to those few which have been illustrated.

Fig. 17 illustrates one and two side modulation. The one side modulation produces very small angles, and thus, very sharp peaks as can be seen by the angle a which has a measurement of eight and one half degrees, the wave pattern representing a frequency of, for example, 4000 cycles, while the two side recording, at 4000 cycles, produces an angle of 17 degrees as seen in b. Therefore, it can be seen that the two side recording is more accurate, and in photographing, it permits greater sharpness. When there is limited space for sound track patterns, I prefer to use the two side modulation.

Fig. 18 illustrates the difference between one side and two side modulation, as a and b respectively, when the wave pattern has many characteristics. It can be seen that much greater angles are obtained by two side modulation, providing more room for the peaks, permitting of greater accuracy.

Fig. 19 represents mathematical synthesis of wave patterns on a drawn graph, the result of which is drawn on a ruled surface as described, for producing a quality film. It can be seen that the wave 59 can be used for low frequencies, rather than for high. Since the wave is larger than the width of the scanning slit, the peaks can be easily photographed for use in covering, for example, the first two and one half octaves. However, for higher frequencies, the wave length becomes more condensed, which calls for simplification of the wave form. 60 represents the simplification of wave 59 to cover, for example, from the first two and one half octaves to the fifth octave. 61 represents the simplified wave for covering, for example, the fifth to the sixth octave, and 62 represents the simplified wave 59 to cover for example, the sixth to the seventh octave. This simplification is accomplished by 75

choosing correct intensities of the constituent harmonics.

This musical system also provides that several tones can be produced from one wave pattern.

5 For example, by the pressure of one key, a chord can be produced, for obtaining predetermined tone qualities. The effect is similar to that of a conventional pipe organ, on which a chord is sustained with various tones, by the pressure 10 of several manuals. The advantage of my invention is that the quality is predetermined and obtained from a single quality pattern. Regarding my methods of synthesis I would call 15 attention to my patent, Number 1,948,169, dated February 20, 1934; my co-pending patent application filed February 11, 1930, Serial Number 427,628, and allowed; my application filed June 16, 1931, Serial Number 544,821, and allowed; my application filed April 3, 1931, Serial Number 527,391, and allowed; my application filed July 31, 1930, Serial Number 472,042; my application filed June 4, 1932, Serial Number 615,307; and also my application filed August 23, 1933, Serial Number 696,361.

20 Figs. 20, 21, and 22 show three different waves which are modified for recording at different frequencies as explained with reference to Fig. 19. The original waves *a*, *a'*, and *a''*, cover approximately the first two and one half octaves, while *b*, *b'*, and *b''* cover approximately from the first two and one half octaves to the fourth octave, *c*, *c'*, and *c''* cover approximately from the fourth octave to the fifth and one half octave, and *d*, *d'* and *d''* cover approximately from the fifth and one half octave to the seventh octave, and so forth. Beside this simplification 35 modulation, changes in wave form also come about by changes in frequency, due to the difference in wave lengths.

40 Fig. 23 illustrates one unit of a commercial assembly, which includes keyboard, pedals, motors, etc., as represented in Figs. 1 and 3, the parts being recognized by referring to the descriptive matter pertaining to said figures. 45 However, a slight change in adjustment is illustrated in Fig. 23, wherein *9'* represents a pedal which is provided for inserting the variable translucency tremolo disc *8* in the path of light passing into lense *7*. The manually operated 50 knob *9* is equivalent to the pedal *9* shown in Figs. 1 and 3, for the purpose of controlling the revolutions of disc *8*.

Fig. 24 is a view of a complete electronic musical instrument housed in a cabinet *76* of commercial design, comprising two independent units such as that shown in Fig. 23, each said unit having its own keyboard, and also a reproducing apparatus for additional musical effects and expressions, as shown in Fig. 2. The various control levers, the volume indicating means, the keyboards, pedals, etc., can be recognized by their numerals, which are the same as those given in previous and following descriptions.

Fig. 25 represents the wiring for a musical 65 instrument as shown in Fig. 24, with the exception of the reproducing apparatus, *a* and *b* represent individual units as shown in Fig. 23, whose light sensitive elements, which may be single or a plurality connected in series, and pre-amplifiers have connection to a mixer, as shown. The additional gain and power amplifier feeds the speakers *63*, *64*, and *65*, which have various frequency ranges, and are housed inside the cabinet *76* of the instrument and also placed at 70 any distance. For the purpose of silent practice,

so that others cannot hear the output, the operator is provided with a head-phone attachment as *66*, see my patent of August 29, 1933, Number 1,924,713.

For the purpose of utilizing the amplification system of the instrument for announcing, the public address system microphone *67* is provided. Also, if it and line *71* is desired to reproduce recorded electrical music, the phonograph pickup *68* with line *78* is connected as shown. These 10 various selective connections make the instrument a universal one.

In Fig. 26, the units *a* and *b* are shown with their light sensitive elements, pre-amplifiers, and mixers as in Fig. 25. However, in addition, the unit *c* is shown, provided for utilizing the reproducing device as shown in Fig. 2. All of the pre-amplifiers are shown connected to a centralized mixer to be transmitted over *69* to distant gain and power amplifiers and from thence to feed 20 speakers as in Fig. 25.

66' and *67'* are provided for silent practice and speech and singing amplification, respectively. The AC line *70* supplies a rectifier with current to feed the light sources as *18*, and the pre-amplifiers of units *a* and *b*. Fig. 26 illustrates the wiring of a complete AC operated musical instrument with the expressional reproducing device as shown in Fig. 2.

Fig. 27 represents the combination wiring of 30 a type used in an orchestra which is composed of a plurality of my electronic musical instruments. *a*, *a'*, *a''*, etc., are units as *a* and *b* of Figs. 25 and 26, with head-phone connections *66''* and microphone connections *67''*, which are connected to the mixer of each unit. A conductor of the orchestra controls all of the individual units by means of the centralized mixer *71*, and, in order to visualize the output of each unit as well as the intensity of the combined outputs of 40 all the units, he switches on and off, at desired intervals, the oscillograph *72*.

Current from the mixer is transmitted to additional gain and power amplifiers. Each of said amplifiers feeds its own individual banks of 45 speakers of different frequency ranges as *73* and *74*.

All explanatory and dimensional figures used in this specification are not to be taken precisely, since they have been cited for the sake of illustration.

Having thus described my invention, what I claim as new and useful is:—

1. A photoelectric musical system, comprising a console for housing electrical tone generating 55 units and an electrical tone reproducing unit, all having a common amplification and sound emitting system, each of said electrical tone generating units comprising an individual standard keyboard, a bank of shutters, each of said shutters 60 in said bank being individually connected to its own co-operative key in said keyboard, a set of diminishing rollers for supporting and individually closing each of said shutters in said bank, automatic means for individually closing said 65 shutters, a pedal operated speed control for varying the revolutions of all diminishing rollers in said set, means for connecting and disconnecting the diminishing means, a light source, a stationary single aperture light limiting mask in the 70 front of said light source, a single optical system for the projection of light of said light source, in predetermined variable amounts, onto a photoelectric element, a photoelectric element, a stationary light limiting single aperture mask in 75

front of said photoelectric element, a uniformly repeating light scanning pitch means operating in conjunction with said optical system, a synchronous motor for driving said scanning pitch means and maintaining international pitch, means for varying the speed of said scanning pitch means, for flattening and sharpening the international musical pitch, a stationary pre-adjustable quality belt mask for selectively and 5 individually modulating the intensity of said predetermined pulsating light energies which are produced by said scanning and projecting pitch means, said quality belt mask comprising a plurality of different specially and synthetically prepared sections, each of said sections having a predetermined number of vertical rows of translucent patterns and apertures of predetermined shapes and sizes, manual means for preadjusting any of said different sections in said quality mask 10 in register with said scanning pitch means, swell pedal means, tremolo pedal means for controlling the increase and decrease in intensity in predetermined selective beats, per predetermined fraction of time, in said light energy, means for 15 indicating and registering the amount of light energy impressed on said photoelectric element, said electrical tone reproducing unit comprising a keyboard, a bank of shutters, each of said shutters in said bank being individually connected to its own co-operative key in said keyboard, a set of diminishing rollers for supporting and individually closing each of said shutters in said bank, automatic means for individually closing said shutters, a pedal operated speed 20 control for varying the revolutions of all said diminishing rollers in said set, means for connecting and disconnecting said diminishing means, a light source, a stationary single aperture light limiting mask in the front of said light source, a single optical system for the projection of the light of said light source in variable amounts onto a photoelectric element, a photoelectric element, a stationary light limiting single aperture mask in front of said photoelectric 25 element, a uniformly repeating scanning means operating in conjunction with said optical system for the projection and production of a predetermined number of pulsating light energies from said light source, a synchronous motor for driving said scanning means and for maintaining precisely international musical 30 pitch, means for adjusting the speed of said scanning means, tremolo pedal means for controlling the increase and decrease in intensity of predetermined selective beats in said predetermined amounts of light energy before said light 35 has been impressed on said photoelectric element, swell pedal means for controlling the intensity of the predetermined light energy before said light energy is impressed on photoelectric element, an electrical tone generating unit, a stationary preadjustable quality belt mask for the selective and individual modulation of the intensities of the pulsating light energies produced by said scanning and projection means, said quality mask comprising a plurality of different 40 sections which have been specially and synthetically prepared by a recording means, each of said sections having a predetermined number of rows of translucent patterns and apertures of predetermined shapes and sizes, recording 45 means, means for preadjusting any of said different sections in said quality mask in register with said scanning means, a motor driven turn table with a phonograph record electrical pick-up coupled into a common amplification system 50 and a sound emitting system of said electric musical system, a common amplification system comprising a plurality of individual preamplifiers and a common power amplifier, a microphone pick-up coupled with said common amplification and sound emitting system of said electric musical system, a head-phone attachment for silent practice, a plurality of monitor loudspeakers 55 and a plurality of loudspeakers at a predetermined distance.

6. In combination, an electric musical system comprising a console, a plurality of electrical tone generating units, an electrical tone reproducing unit, a transcription table with a phonograph pick-up, a microphone pick-up, a head-phone attachment, and a common-for-all amplifying and sound emitting monitor and distant system, said tone reproducing unit and each of 65 said tone producing units comprising independent identical means, as, an individual keyboard, a bank of shutters, each of said shutters being individually connected to its own co-operative key in said keyboard, a set of diminishing rollers for said bank of shutters, for individually supporting and automatically closing each of said shutters at a predetermined fraction of time, means for connecting and disconnecting the action of said diminishing means, a motor for driving said set of diminishing rollers, a pedal operated speed control for varying the revolutions of all said diminishing rollers, a light source, a stationary single aperture light limiting mask, in front of said light source, a single optical system for projecting the light of said light source 15 in variable amounts onto a photoelectric element, a photoelectric element, a stationary light limiting single aperture mask in front of said photoelectric element, a uniformly repeating scanning means operating in conjunction with said optical system for the projection and production of a predetermined number of pulsating light energies from said light source, a synchronous motor for driving said scanning means and for maintaining precisely international musical 20 pitch, means for adjusting the speed of said scanning means, tremolo pedal means for controlling the increase and decrease in intensity of predetermined selective beats in said predetermined amounts of light energy before said light 25 has been impressed on said photoelectric element, swell pedal means for controlling the intensity of the predetermined light energy before said light energy is impressed on photoelectric element, an electrical tone generating unit, a stationary preadjustable quality belt mask for the selective and individual modulation of the intensities of the pulsating light energies produced by said scanning and projection means, said quality mask comprising a plurality of different 30 sections which have been specially and synthetically prepared by a recording means, each of said sections having a predetermined number of rows of translucent patterns and apertures of predetermined shapes and sizes, recording 35 means, means for preadjusting any of said different sections in said quality mask in register with said scanning means, a motor driven turn table with a phonograph record electrical pick-up coupled into a common amplification system 40 and a sound emitting system of said electric musical system, a common amplification system comprising a plurality of individual preamplifiers and a common power amplifier, a microphone pick-up coupled with said common amplification and sound emitting system of said electric musical system, a head-phone attachment for silent practice, a plurality of monitor loudspeakers 45 and a plurality of loudspeakers at a predetermined distance.

3. A multi-manual console tone producing and tone reproducing electric organ with an electrical phonograph attachment for self-playing and a sound amplifying microphone pick-up, both working through a common amplifying and sound emitting system, said organ comprising a sectional belt mask with parallel multi-tracks, each section of said belt mask having a predetermined number of sound tracks for producing tones of different predetermined pitches and the same 50 quality, said sound tracks of each section being recorded and synthetically prepared, each said track representing the predetermined pitch of a musical tone and always being in the same predetermined location in all sections of said belt 55

- mask, uniform repeated patterns of predetermined linear dimensions, usually termed as wave length, in each predetermined sound track of said belt mask being synthetically prepared in 5 linear scale in proportion to the frequency of the musical tone which said sound track produces, uniformly repeating patterns in each sound track of a predetermined section of said belt mask, of predetermined shape, usually 10 termed as wave form, being synthetically prepared in design for predetermined quality of the musical tone which said sound track produces, each said sound track continuing through all sections without mismatching, and being made to 15 produce tones of the same pitch in all sections of said belt mask.
4. In a multi-manual electric organ, a console having a plurality of independent electrical tone generating units and one electrical tone reproducing unit, all coupled to a common amplifier and common sound emitting system, each of 20 said units comprising a keyboard, a bank of shutters, an automatic tone diminisher, a light source, a single optical system, a synchronous motor, 25 means for producing independently a plurality of tones of predetermined pitch and predetermined quality, a swell pedal means, tremolo means, and a photoelectric element with electrical connections to said common amplifying and 30 sound emitting system.
5. A multi-manual console electronic organ housing one and more independent electrical tone generating units, a common amplification system, a common sound emitting system, an external phonograph self-playing attachment, and 35 a sound amplifying microphone pick-up, comprising a plurality of synthetically made belt masks, one for each said tone generating unit, each said belt mask being assembled from a plurality of different synthetically prepared and recorded belt sections of predetermined length, each of said belt mask sections bearing a plurality of parallel sound tracks, each said sound track in each said belt mask section being assembled 40 into one row of sound tracks without mismatching, each of said matched sound tracks through all of said sections being synthetically made to produce only one predetermined pitch of musical tone, each of said matched sound tracks of all said belt sections being made to 45 produce tones of the same pitch and different predetermined qualities, one in each of said different sections, individually and synthetically recorded by recording means from manually prepared wave form patterns, predeterminedly and 50 mathematically prepared by the Eremeeff-Helmholtz synthesis of fundamental frequencies in combinations with partials and sub-partials of predetermined intensity for modulation of said fundamental, a plurality of common optical scanning means, one of said means for each of said tone generating units, a light source, keyboard, and photoelectric element for each of said tone generating units, a microphone pick-up, an electrical phonograph and electrical phonograph pick-up, and a common-to-all amplification and sound emitting system.
6. In a multi-manual electric organ with individual tone generating and tone reproducing 55 units, a synchronous motor for each of said units, for maintaining precisely the international musical pitch of said organ in all of its manuals, said synchronous motors operating on the cycles of an alternating electric current supply, without changing their speed from voltage variation
- of said alternating current, an electric current supply feeding said motors, and a brake with adjustment for each of said motors for varying the load of each of said motors.
7. In a multi-manual electric musical instrument of the class described, the combination of a plurality of tone generating units, each of said units co-operating with its own manual, a manual including a number of keys, a single shutter operated by each of said keys, a diminishing attachment, a light source, a stationary preadjustable quality belt mask, a moving scanning belt mask, a synchronous motor, a single optical system for projecting said light energy through said stationary and moving belt masks in predetermined register onto a photoelectric element for conversion of said light energy into sound energy. 10
8. In a multi-manual electric organ, a plurality of tone generating units, each having:—a keyboard, a set of shutters, a light source, a quality belt mask, means for presetting said mask, a rotary scanning element, a synchronous motor for driving said scanning element, a common optical system for projecting and moving in one direction a filament of the said light source, by 15 said rotary scanning means, on a predetermined area of the said quality belt mask, means for producing a preadjustable beat tremolo, and means for metering the output of each of the 20 said tone generating units.
9. In a multi-keyboard electronic organ, a keyboard operated electrical tone reproducing unit, a keyboard, a bank of shutters, a diminisher, a single filament source of light, a stationary light gauging mask, a single optical system for projecting the said filament of light source across one and more sound tracks of the quality mask, a multi-track quality mask with sound tracks of predetermined pitches and predetermined qualities, a synchronous motor drive, a musical key 25 changing means for said synchronous motor drive, a single photo-electric element, a variable beat tremolo attachment, and a graduated volume control.
10. In an electrical musical instrument in which musical tones of predetermined quality and pitches are produced, a keyboard, a set of shutters, each shutter connected to its own cooperative key in said keyboard, a diminishing attachment for automatically closing the manually 30 opened individual shutters of the keys of said keyboard, means for predeterminedly presetting a rate of time for diminishing the electrically produced tones, and means for connecting and disconnecting said diminishing means.
11. In a multi-manual electrical musical instrument in which musical tones are produced and reproduced photo-electrically in conjunction with multi-track sound records and the action of keyboards; light sources, photo-electric elements, 35 synthetically prepared stationary and moving track record masks, keyboards with sets of shutters, one of said shutters for each sound track, and a single common optical system for each of the tone producing and reproducing units, for the simultaneous selective projection and scanning by said light source, one and more sound tracks of the said stationary and moving multi-track mask.
12. A photo-electrical organ, comprising, a keyboard, a set of shutters, a diminisher, a single filament light source, a single common lens for projecting and focusing on a multi-track belt record predetermined portions of said single filament of said light source, when selected shutters have 40

- been opened by the action of their cooperative keys of said keyboard, a multi-sound track belt record of predetermined length with a plurality of parallel sound tracks of periodic wave patterns of recorded and synthetically prepared sound, each of the said sound tracks being made to produce one predetermined pitch and predetermined quality of sound, a synchronous motor with a drive for moving in a predetermined selected direction at a constant uniform speed, the said multi-track sound record, and a multi-track belt drive with a speed changer for predeterminedly and simultaneously varying the the key in all of the said multi-tracks of said belt record.
13. A photo-electric organ comprising; means for keying and optically scanning by light a moving multi-track record, a multi-sound track belt record with sound tracks, each track having a predetermined pitch of sound and a non-periodic predetermined quality of sound, and a synchronous motor drive with a speed changer for the simultaneous and selective playing of all of the said sound multi-tracks at a predetermined different musical key.
14. A method for tuning and keeping in tune at a predetermined international musical pitch, one and more predeterminedly designed electro-mechanical units, each of which is made for generating individually one and more predetermined musical tones electrically, said units operating from a commercial source of alternating electric current power supply of predetermined fixed frequency and variable voltage, by driving each of the said independent electro-mechanical tone generating units, with the aid of a synchronous motor of predetermined speed and cycles, said synchronous motor being subject to variation in speed only from the variation of the cycles and not from the fluctuation of the voltage of the A. C. current on which the said motor is operating.
15. A method for generating electrically a plurality of musical tones at constant uniform pitches in perfect tune with the standard international musical pitch, using a standard commercial source of electrical energy of a fixed number of cycles and a fluctuating voltage for driving the electrical tone generators, by driving said electrical tone generators using an electric motor designed to operate only on the cycles of the said commercial electrical current supply, and the number of revolutions of the said electric motor, the number of cycles of said commercial electrical current, and the frequency of the predetermined selected electrically generated tone always staying in the exact same proportion at a predetermined fraction of time, even when the voltage of the said commercial electric current has been unavoidably varied.
16. In an electrical musical instrument for producing musical tones photoelectrically, a keyboard with a set of light shutters, a light source with a single filament of a predetermined dimension, a preadjustable stationary belt mask with a predetermined number of rows of apertures of predetermined size and shape, a synchronous motor for uniformly rotating in a predetermined direction a multi-sided pitch scanner for reflecting and successively projecting a predetermined portion of the image of the lighted filament of said light source when predetermined shutters have been opened by the action of their co-operative keys in said keyboard, through predetermined apertures of said belt mask into a photoelectric element.
17. In a multi-manual electronic organ with in-
- dividual tone generating units, a plurality of keyboards, a plurality of shutters, light sources, stationary and moving belt masks with rows of apertures for modulating the light passing through them, a plurality of optical systems for focusing and projecting the images of said light sources through the apertures of said belt masks, synchronous motor drives for moving said belt masks, preadjustable beat vibrato means for each of said tone generating units, and means for controlling the volume of sound from each of said tone generating units.
18. In a machine of the class described, the combination of a set of shutters, a light source, an automatic diminisher, a keyboard, an optical slit multi-scanning means, a lens, a preadjustable quality belt mask, a photoelectric element, and a galvanometer metering means, including said common light source, an optical system, a galvanometer, a rotary disc with predetermined rows of perforations, a photoelectric element, and amplifying and registering means, said metering means operating in synchronism with said scanning means, for measuring and indicating the intensities of the output of said machine under different predetermined conditions.
19. In a multi-manual photoelectric organ, light sources which are controllable by the action of keyboards, optical scanning means, a plurality of synthetic sound-on-film moving and stationary belt masks, and photomechanical means for the synthetic preparation of said moving and stationary belt masks, said masks bearing a plurality of sound tracks of different predetermined pitches, volumes, and qualities.
20. In a multi-manual photoelectric musical instrument, a plurality of light sources, a plurality of optical systems, a plurality of optical light scanning means, synchronous motor drives, a plurality of preadjustable sectional belt masking means, the predetermined sections of which are predeterminedly scanned by said light scanning means, each section of said belt mask being manually, synthetically, and photomechanically prepared, for the production of tones photoelectrically, said tones having predetermined pitches, qualities, and volumes, in conjunction with light sources, scanning means, and a photoelectric element.
21. In a multi-manual photoelectric organ, a plurality of moving and stationary belt masks, each bearing multi-track sound records in parallel rows, said belt masks being predeterminedly and synthetically prepared by manual delineations, and photo-mechanically with a flat field corrected optical system recording means, for the production of predetermined sounds of predetermined pitches, volume, and synthetic qualities, the complex wave patterns used in the production of sound tracks in said masks being obtained by Helmholtz synthesis and Eremeeff synthesis of sub-partials modulating fundamentals, Eremeeff spreading, condensing, and altering synthetically produced sound track patterns, and Eremeeff gradual simplification of the shape of the predetermined wave forms from low to high pitches, for photoelectrically produced sounds.
22. In a photoelectric musical system, one and more moving predeterminedly recorded and synthetically prepared multi-track sound-on-film endless belt mask records of predetermined length, for the production of sounds of different predetermined pitches of a musical scale, different predetermined qualities, and different predetermined volumes, said multi-tracks of said belt mask records being predeterminedly recorded for prede-

terminated fixed pitches, and predetermined fixed qualities, predeterminedly recorded for predetermined fixed pitches and non-periodic qualities, and predeterminedly recorded for non-periodic 5 pitches and nonperiodic qualities, a synchronous motor drive with a speed changer of fixed steps for driving said multi-track belt mask records, a flat field optical system for simultaneously projecting and scanning all of said multi-tracks, a 10 light source, a keyboard with flexibly connected shutters, and a common amplification and sound emitting system.

23. In a photoelectric musical instrument, a multi-sound-track continuously running belt record, which has been predeterminedly recorded and synthetically prepared, a key-operated shutter for each of said sound tracks, a keyboard, a light source, one optical system for scanning all of said tracks simultaneously, a photo-electric element, 15 a synchronous motor drive with a gear box and a predetermined speed changer, an automatic diminisher with a variable diminisher time control, an automatic vibrato with variable beat volume control, an electrical phonograph pick-up, a microphone pick-up, a mixer, and a common amplifying and sound emitting system.

24. A multi-manual photoelectric organ, comprising a plurality of keyboards, with standard hollow metal keys, and a typewriter type keyboard, each key of said keyboards being connected to its co-operative individual light shutter, a plurality of sets of light shutters, a plurality of automatic motor driven diminishers with off and on connecting means for each individual diminisher, a plurality of stationary and moving multi-track quality masks, a light source for each of said quality masks, a flat field corrected lens for each light source, a monitor set of speakers, an echo organ set of speakers, and a complete electrical phonograph, and phono-pick-up monitor and distant microphone, switched on and off from the console of said multi-manual organ.

25. A photoelectric musical instrument com-

prising a plurality of endless belt masks bearing a plurality of sound tracks synthetically and predeterminedly recorded for the production of sound photoelectrically, said sound having predetermined pitches, qualities, and volumes, a plurality of light shutters, one light shutter being provided for each of said sound tracks, a plurality of keys co-operating with their own light shutters, an optical system for each of said endless belt masks, a light source, automatic diminishing means, a synchronous motor drive for moving said belt masks, a photoelectric element for each of said belt masks, and a common amplification and sound emitting system for said plurality of belt masks.

26. A photoelectric musical instrument comprising one and more electrical tone generating units, each said unit comprising a light source, a set of shutters, a set of keys for opening and closing said shutters, an endless moving pitch belt mask, a stationary quality belt mask, a flat field corrected optical system, a synchronous motor with a brake for predeterminedly varying its speed, a photoelectric element, for each of said tone generating units, a set of monitor speakers, 20 a set of distant speakers for producing echo effects, a microphone, a synchronous motor driven phonograph turn table with an electrical phonograph pick-up, and a common-for-all amplification system.

27. In an electric organ, a keyboard, a set of shutters cooperating with the keys of said keyboard, a diminisher, a light source, an optical system, volume controlling means, tremolo producing means, a multi-sound track moving record, each individual sound track of said record having predetermined pitch, quality, and volume, and having been recorded in predetermined tune and according to the predetermined law of volume distribution throughout its musical range, and a constant speed motor for driving the said multi-track belt at a predetermined uniform speed.

IVAN EREMEEFF.
